UNITED STATES PATENT OFFICE.

JOHN W. PEARSON, OF SAN FRANCISCO, CALIFORNIA.

DIPPING APPARATUS.

1,401,437.

Specification of Letters Patent. Patented Dec. 27, 1921.

Application filed December 9, 1919. Serial No. 343,480.

To all whom it may concern:

Be it known that I, JOHN W. PEARSON, a citizen of the United States, and a resident of the city and county of San Francisco, State of California, have invented a certain new and useful Dipping Apparatus, of which the following is a specification.

The invention relates to an apparatus for dipping fruit or other perishable or tender articles.

An object of the invention is to provide an apparatus for dipping fruit and other articles of similar nature for a brief predetermined time without injury thereto.

Another object of the invention is to provide means for submerging and withdrawing a tray of fruit from a bath after a predetermined submersion.

A further object of the invention is to provide means for transferring the dipped fruit from the dipping tray to a drying tray without injury to the fruit.

The invention possesses other advantageous features, some of which, with the foregoing, will be set forth at length in the following description, where I shall outline in full, that form of the invention which I have selected for illustration in the drawings accompanying and forming part of the present specification. In said drawings I have shown one specific form of apparatus of my invention, but it is to be understood that I do not limit myself to such form, since the invention, as set forth in the claims, may be embodied in a plurality of forms.

The apparatus is particularly adapted to dipping bunches of grapes, prior to drying, but it is to be understood that it is equally applicable to all articles which require dipping in a bath or solution. The rapid and economical drying of grapes by artificial heat requires that the grapes be dipped in a lye bath, to partially disintegrate the skins, prior to being placed in the drying chamber. The skins of grapes are very tender and the time of contact of the grapes with the lye solution must be accurately measured if proper results are to be obtained. Some grapes will require six seconds contact and others, that is, grapes of a different nature, will require eight seconds,

and so on, and it is important that grapes requiring a six second contact, for instance, be given a contact of that duration and not materially more or less. A shorter contact 55 will not produce the desired effect upon the skins and a longer contact will break or destroy the skins, and reduce the grapes to a practically valueless pulp. It is necessary therefore, that the time of contact of the 60 grapes with the lye solution be carefully and accurately adjusted.

Economically it is impossible to dip the grapes a bunch at a time, and the bunches of grapes are consequently arranged in a 65 tray having a perforated or foraminous bottom and the loaded tray submerged in the solution. The specific gravity of grapes is only slightly greater than that of the solution, so that if the tray is plunged or 70 forced into the solution, the grapes will float, and consequently become disarranged, pass over the edge of the tray and become generally messed up. In the apparatus of my invention the loaded tray is permitted to 75 sink gently into the solution, so that the grapes become submerged without becoming disarranged. Similarly, if the tray is raised quickly in the solution, the grapes are forced to the bottom of the tray, closing or partly 80 closing the apertures or openings therein, so that the grapes are crushed and the raised tray is filled or partly filled with the solution. In my apparatus I prevent this, by slowly raising the tray through the solution 85 so that the solution may pass through the bottom without material obstruction.

I have found that it is not practical to dry the grapes in the trays in which they are dipped and have provided means for transferring the dipped grapes from the dipping tray to the drying tray. The dipping tray is preferably made of metal, since the metal is not affected by the lye solution and since it does not become soaked as a wooden tray 95 would. Further, should a wooden tray be used for dipping and drying, the tray would soon become incrusted with lye which would be extremely deleterious to the hands of the operators handling the trays. Other disadvantages of using the same tray for dipping and drying are apparent, 100

and I therefore prefer to use a metal tray for dipping and then transfer the grapes to a wooden tray for drying.

The apparatus of my invention is substantially automatic, operating to slowly submerge and raise the tray in the lye solution, repeat this operation in a wash bath, such as water and transfer the grapes to the drying tray.

10 In the accompanying drawings I have shown one form of apparatus for carrying out the process of my invention. Referring to said drawings:

Figure 1 is a side elevation, partly in section, of the apparatus of my invention.

Fig. 2 is a plane or top view of the apparatus.

Fig. 3 is an end elevation of the apparatus.

Fig. 4 is a section taken across Fig. 1.

15 Fig. 5 is a plan view of a dipping platform.

Fig. 6 is a fragmentary view showing the conveyer bar in contact with a tray.

Fig. 7 is a fragmentary view of a portion 15 of conveyer chain showing the platform tripping device.

Fig. 8 is a fragmentary view of a portion of the platform dipping mechanism.

Fig. 9 is an elevation of a dipping station, the broken lines showing the position of the parts with the platform submerged.

Fig. 10 is a side elevation of the tippling device, the broken lines showing the position of the device when being overturned.

35 Fig. 11 is a fragmentary top view of the tippler device.

Fig. 12 is an end elevation of the tippler device.

40 Fig. 13 is a perspective view of a dipping tray.

The apparatus includes a dipping station, a washing station and a transferring station, a conveyer for moving the filled tray to the dipping station, receiving the dipped tray

45 and moving it to the washing station and receiving the washed tray and conveying it to the transferring station.

The dipping station comprises a suitable tank or vessel 2, preferably made of metal

50 and of rectangular shape, which is arranged over a suitable heater or furnace 3 so that the lye solution in the tank may be kept warm. Arranged above the tank is a platform 4 comprising two spaced angle irons

55 5 extending longitudinally with respect to the tank and suitably connected together by rods or angles disposed below the lower flanges thereof to form a substantially rigid structure. The lower flanges of the angle

60 bars are turned inwardly to form a track on which the dipping tray slides. The platform is of less width and length than the tank, so that it may be submerged in the solution in the tank. The platform is pro-

65 vided on opposite sides with supporting

bails 6, preferably made of metallic rods, which are secured at their upper ends to the cables 8 which pass over the sheaves 9, journaled on the frame 12. At their other ends the cables are attached to the lever frame 13, pivoted to the frame 12 below the sheaves. Attached to the outer end of the lever frame 13 are counterweights 14, the effective pull of the counterweights on the cables being greater than the weight of the platform and the loaded tray. Upward movement of the frame relieves the platform of the counterweights and permits it to sink, with the loaded tray, into the lye solution tank.

80 Means are provided for raising the lever frame 13, to permit the tray to sink, then releasing the frame 13, so that the counterweights become effective to gently raise the filled tray through and from the solution, and the operation of this means is timed and adjustable, so that any desired time of contact, within the range of the apparatus, may be obtained. Arranged in front of the frame 12 is a loading frame 15', upon which and upon the frame 12 are arranged tracks 15 which are alined with the angle bars 5 of the platform, when the platform is in the raised position. These tracks 15 are preferably formed of angle bars and the ends of the angle bars are closely adjacent, so that practically a continuous track is produced. Mounted on the frame 15' are sprockets 16 over which pass endless parallel conveyer chains 17 which are connected together by the cross rods 18. The lower run of the chain passes along the angle bars and across the frame 12 on the outside of the angles and with the rods 18 bearing against the upper edges of the angle bars. The cross rods are spaced apart a sufficient distance to accommodate a dipping tray 19 between them, and the trays are deeper than the angle bars, so that they project above the angle bars and are propelled along the track by the cross rods. The tray is thus moved from the loading or feeding platform 15' into the dipping platform.

85 Pivoted to the frame 12 at opposite sides thereof are levers 21, in the shape of bell crank levers, having their depending arms 22 lying adjacent the chains 17. At their upper free ends, the levers 21 are provided with rollers 23 engaging under the lever frame 13. Movement of the arms 22 to the right (which is the direction of movement of the lower run of the chains) causes the lever frame to be raised relieving the dipping platform of the counterweights and permitting it to sink. Secured to the chains, at spaced predetermined points, are dogs 24, which engage the arms 22 and move them to release the dipping platform. The counterweights are held suspended as long as the dogs are in engagement with the

arms 22, and by varying the length of the arms, the time of suspension of the counterweights and consequently the time of dipping of the fruit is made variable. The 5 arms are made in two parts, secured together by bolts; so that their length may be varied.

The loaded dipping tray is moved over the feeding platform into the path of the 10 cross bars of the conveyer and a cross bar engages behind the tray and pushes it onto the dipping platform. The dogs on the chains then engage the arms 22, allowing the tray to move downward away from contact with the cross bar, which passes onward. The dogs are so placed that the tray is 15 released from the conveyer when it is properly positioned on the platform.

The tray sinks slowly through the lye 20 bath and, after the arms 22 clear the rollers 23, then moves slowly upward through the lye solution in position to be engaged by another cross bar on the conveyer. By permitting the tray to slowly sink, the grapes 25 are not disarranged and by raising it slowly, the grapes are not crushed by the pressure of the solution. The now engaging cross bar moves the tray from the dipping platform, over the connecting angle bar tracks 20 25 into the washing dipping platform 26, which is of the same construction as the lye solution dipping platform. Disposed below the platform 26 is a wash water tank 27, into which the loaded tray is submerged. 30 This platform is similarly suspended from counterweights 28, carried by the lever frame 29 which is raised by the levers 31 by contact with the dogs on the chains. The loaded tray is thus permitted to sink 35 into the wash water and is slowly raised from the wash water so that the grapes are not disarranged or injured. When the tray is raised to its normal track level by the platform, it is engaged by another cross- 40 bar on the conveyer and moved from the platform 26 onto the tracks 32, to a transferring mechanism which transfers the grapes from the metal dipping tray to the wooden drying tray. As the metal tray 45 passes from the washing platform to the transferring mechanism, a drying tray is placed up-side-down over the dipping tray and in the transferring mechanism, the two trays are turned over together to transfer 50 the grapes from the dipping tray to the drying tray. In order to prevent the grapes from sliding to one edge of the tray during the turning over, the dipping tray is provided with a plurality of upward exten- 55 sions, preferably in the shape of transverse vertical walls 33, which divide the tray into a plurality of compartments. These walls 60 33 extend upward to the upper edge of the dipping tray and contact with the bottom 65 of the superposed drying tray 34, so that

when the trays are turned over, there is no appreciable bodily movement of the grapes to one side of the tray.

The tipping or turning over device comprises a frame or open ended box-like structure 35, into which the superposed trays are pushed from the tracks 32 by the cross-bar. The frame lies between the chains and is normally supported by the cross members 70 36. The ends of the frame are flared to 75 produce enlarged ends to permit the ready insertion of the superposed trays. The frame is pivoted at its center to levers 37, which are fulcrumed above the frame and which normally lie at an angle to the plane 80 of the track, and which are provided with suitable counterweights 38. At the open ends of the frame or tipple, are side plates 39, having seats 41 formed therein in position to be engaged by the cross-bars on the 85 conveyer. The tipple frame is of less length than the tray and the trays are pushed partly through the frame before the cross bar enters the seats 41. The continued movement of the cross-bar bearing against 90 the end of the frame and carrying such end, causes the tipple frame to rise and turn over, the frame turning on its pivot and the levers 27 moving on their fulcrums. To prevent the frame from tilting before the 95 cross-bar engages the seats, I have provided a latch 42, engaging a lug 43 on the frame, which latch is connected to the tipping lever 44, which is engaged by the leading end of the dipping tray, as the cross-bar engages 100 105 in the seat. When the tipple frame turns over, the trays are turned over and the projecting ends thereof are then disposed at the left end of the tipple frame. The next trays being moved forward by the conveyer, push 110 the inverted trays from the tipple frame onto the platform 45, where the dipping tray is removed and placed on the runway 46, over which the upper run of the conveyer travels, for transport back to the feeding 115 platform. At the tipple end of the apparatus the conveyer chains pass over the drive sprockets 47 to which a suitable prime mover is connected by the belt 48. The conveyer passes over the tipple mechanism onto the runway 46.

The grapes are thus automatically and carefully dipped for a predetermined time, are automatically washed and then transferred to the drying trays and the dipping trays returned to the feed platform. In this manner, a few metal dipping trays only are required to handle a large crop and fill a great number of drying trays.

I claim:

1. The system for treating fruits to be dried, which consists of placing the fruit in one of a series of dipping trays, introducing the tray into a continuously operative conveyer, successively transferring the tray by 120 125 130

said conveyer into successive baths of lye and water respectively, applying a drying receptacle to the tray after leaving the water bath, and then inverting the tray and the

5 receptacle to transfer the fruit from one to the other so that the dipping tray may be returned to the conveyer for re-use.

2. A continuously operating, automatic fruit dipping apparatus comprising a tank, 10 a tray platform operatively mounted and arranged above said tank, means for moving the tray onto the platform and means for releasing said platform for downward movement.

15 3. A dipping apparatus, comprising a series of bath tanks, dipping platforms operatively mounted and arranged at the tanks to carry trays thereinto, and means operative to move trays onto and for controlling the operation of, the platforms.

4. A dipping apparatus, comprising a series of bath tanks, dipping platforms operatively mounted and arranged at the tanks to carry trays thereinto, and continuously 25 acting means operative to move trays onto and for controlling the operation of, the platforms.

5. An apparatus of the character described, comprising a tank, a vertically movable tray support arranged above said tank and adapted to receive a tray of fruit, means for moving said tray onto said support and means operative by the moving means for releasing said support for downward movement.

6. An apparatus of the character described, comprising a tank, a vertically movable tray support arranged above said tank, a conveyer for moving a tray onto said support, a counterweight normally holding said support in the raised position, and means for releasing said counterweight from the support so that the support moves downwardly.

45 7. An apparatus of the character described, comprising a tank, a vertically movable tray support arranged above said tank, a conveyer for moving a tray onto said support, a counterweight normally holding said support in the raised position, and means for raising the counterweight to permit the support to descend into the tank and for releasing the counterweight to raise the support from the tank.

55 8. An automatic apparatus of the character described, comprising a tank, a tray support arranged above the tank, means for releasing the tray support to permit the tray to sink into the liquid in the tank, and a counterweight for raising said tray from the liquid.

9. An apparatus of the character described, comprising a tank, a tray support arranged above the tank, means for releasing 60 the tray support to permit the tray to sink

into the liquid in the tank, a counterweight for raising the tray from the liquid, and means for timing the contact of the tray with the liquid.

10. An apparatus of the character described, comprising a tank, a tray support arranged above the tank, a counterweight connected to said support, a conveyer for moving a tray onto said support, and means operative by the conveyer for holding said counterweight elevated for a predetermined time.

11. In an apparatus of the character described, a tank, a tray support suspended above said tank, a conveyer for moving a tray onto said support, and means operative by the conveyer for releasing said support to permit the tray to sink into the liquid in the tank.

12. In an apparatus of the character described, a tank, a tray support arranged above the tank and adapted to be reciprocated vertically to dip a tray into the liquid in the tank, and means for timing the duration of contact of the tray with the liquid.

13. In an apparatus of the character described, a tank, a tray support arranged above the tank and adapted to be reciprocated vertically to dip a tray into the liquid in the tank, a conveyer for moving a tray onto said support and means operative by the conveyer for timing the duration of contact of the tray with the liquid.

14. In an apparatus of the character described, a tank, a tray support arranged above the tank and adapted to be reciprocated vertically to dip a tray into the liquid in the tank, and adjustable means for timing the duration of contact of the tray with the liquid.

15. In an apparatus of the character described, a dipping tray, a superposed drying tray, and means for inverting the two trays to transfer the contents of the dipping tray to the drying tray.

16. In an apparatus of the character described, a tipping, reversibly mounted frame and a conveyer for feeding articles into said frame and causing said frame to turn over.

17. In an apparatus of the character described, a tipping frame, a link upon which said frame is mounted, and a conveyer adapted to engage and turn over said frame.

18. In an apparatus of the character described, a tipping frame, a link upon which said frame is pivoted, a conveyer arranged to move articles into said frame and disposed to engage the end of said frame and turn it over.

19. In an apparatus of the character described, a dipping station, a washing station and a tipping station and a conveyer for moving trays successively to the different stations and operating the tipping device.

20. In an apparatus of the character de-

71

scribed, a dipping apparatus, a tippling apparatus, and a conveyer for moving trays from the dipping apparatus to the tippling apparatus and for operating said dipping and tippling apparatus.

21. In an apparatus of the character described, a dipping apparatus, a washing apparatus, a tippling apparatus, a conveyer for moving trays to the three apparatus suc-

cessively and for operating said three apparatus.

In testimony whereof, I have hereunto set my hand at San Francisco, California, this 10th day of November, 1919.

JOHN W. PEARSON.

In presence of—
H. G. PROST.
